UNITED STATES PATENT OFFICE.

GEORGE HILLARD BENJAMIN, OF NEW YORK, N. Y.

GAS-PRODUCER.

1,329,744.

Specification of Letters Patent.

Patented Feb. 3, 1920.

Application filed June 19, 1918. Serial No. 240,731.

To all whom it may concern:

Be it known that I, GEORGE HILLARD BENJAMIN, a citizen of the United States, residing at New York, in the county and State of New York, have invented certain new and useful Improvements in Gas-Producers, of which the following is a specification.

My invention consists in a gas producer adapted to utilize gas producing materials, such as fine coal or culm.

My improved gas producer involves the employment of the following instrumentalities:

(1) A structure having the general characteristics of a tunnel kiln.

(2) Means for heating the interior of the kiln by the combustion of gas and air.

(3) Means for supplementing the heat due to the combustion of gas and air.

(4) Means for holding the gas producing material to be decomposed, and progressively moving the material through the kiln.

(5) Means for causing the products of combustion of gas and air to pass through the gas producing material in the kiln and be carried out of the kiln, as well as other features of construction which will be described in connection with the drawings.

The general object of my invention is to economically and continuously produce a combustible gas.

The accompanying drawings will serve to illustrate my invention, in which:

Figure 1 is a vertical transverse section through the gas producer.

Fig. 2 is a plan view taken on the line II—II of Fig. 3.

Fig. 3 is a longitudinal vertical section taken on the line III—III of Fig. 1.

Fig. 4 is a horizontal longitudinal section, taken on the line IV—IV of Fig. 1.

In the drawings, 5 indicates a tunnel structure, which in general construction, outline, material employed, etc., may conform with that usually employed in tunnel kilns for drying and burning brick, pottery and the like. The body of the kiln is divided transversely into three sections, i. e., 6 the entrance section, 7 the central section, and 8 the exit section. The respective sections are adapted to be separated by vertical moving doors 9, and the outer ends of the

sections 6 and 8 by the vertical moving doors 10. Sections 6 and 8 are preferably made of the required length to contain one car 11, 55 but may be made longer; the central section to contain any number of cars, as desired. The whole length of the kiln should be such as is found necessary to effect complete decomposition of the gas producing material 60 carried by the cars during their passage through the kiln. For ordinary bituminous coal, the kiln may be from sixty to one hundred and forty feet in length; for anthracite coal, between sixty and two hundred 65 and forty feet.

The cars 11 are mounted on wheels 12, which move over rails 13. Opposite rails are respectively connected to the terminal of a dynamo machine 14, through the conductors 42—43, the current from which may be controlled through the rheostat 15. The upper portion 16 of the cars, has inwardly inclined sides and is made of refractory material. Arranged in the bottom of the cars 75 is a grate 17, consisting of a series of spaced bars 18 and a rotary member 19 (see Fig. 2). The bars 18 are provided with gear wheels 18' whereby rotation of one bar by means of rotary member 19 causes rotation 80 of all of the bars. The rotary member 19 is adapted to coöperate with a vertically disposed arm 20, arranged in the path of movement of the car, whereby when the rotary member 19 is actuated, the bars 18 are rotated for the purpose of stirring up the ash in the bottom of the cars over the grates, so that it will be discharged upon the moving chain carrier 21 which receives motion 85 from any suitable source of power, as for instance, the chain 22. By continuously discharging the ash, the passage of the products of combustion through the body of the fuel in the car is not interfered with as would be the case if the ash were allowed to accumulate.

Located about midway in the body of the car, are oppositely disposed electrodes 23. These electrodes 23 are in metallic connection with the wheels 12 of the car through 100 shaped metallic connection plates 44—45. The wheels 12 of the car rest on the rails 13, which rails through conductors 42—43 are connected with the terminals of the dynamo

machine 14. Formed in the body of the car below the electrodes 23, are openings 24, the purpose of which will be hereafter described. Connected with the bottom of the body of the car, are runners 25, which move in channels 26, containing sand or other refractory material. The purpose of the runners 25 and channels 26 is to act as moving diaphragms to protect the lower portion of the car and wheels from the high temperature of the waste gases passing through the fuel in the body of the car and toward an exhaust blower, as will hereafter be described.

Situated at each side of the kiln, are gas and air burners 27, which when ignited, will inject flame on bodies of refractory material 28 located in the pockets or bags 29. Secured to the sides of the car, are runners 30, which move in channels 31 containing sand, the purpose of which is to act as diaphragms to prevent the passage of products of combustion from pockets 29, except through the fuel in the car. 32 indicates flues connected to the flues 33, in turn connected to the inlet of a suction blower 34. The outlet of the blower 34 may discharge into any suitable gas receiver.

The rail 13 on one side of the kiln, is preferably divided into sections 13^a, as shown in Fig. 2, the object of which is to provide for the regulation of the temperature of successive zones along the length of the kiln. To give motion to the cars through the kiln, power is transmitted to shaft 35, through a sprocket wheel 36, which gives motion to chain belt 22. The chain belt 22 is provided with projections 37, which co-operate with depending arms 38 connected to the cars 11. A chain belt 39, corresponding to belt 22, is arranged at the opposite end of the kiln, and this belt is also provided with projections 40, corresponding to 37. It will be understood that movement imparted to belt 22 is transmitted to belt 21 and from belt 21 to belt 39.

The operation of my improved producer is as follows: The fuel to be decomposed is introduced into a car, the car at the time being in the position shown at the left of Fig. 50 3, this position being equal in distance, to the space occupied by two cars. The belt is then started, which moves the car to the position indicated in dotted lines. The belt is then stopped. It being now desired to introduce a car into the kiln, the door 9 at the left hand end of the kiln is lowered and the door 10 raised, and simultaneously the door 9 at the right hand end of the kiln raised, and the belt again started. This moves the car into the position indicated at 55 X at the left hand end of the kiln, and the car into the position indicated at Y at the right hand end of the kiln, the cars in the kiln being correspondingly moved forward, 60 after which the door 9 at the left hand end

of the kiln is raised and the door 10 lowered, the door 9 at the right hand end of the kiln raised and the door 10 lowered. The object of raising and lowering the doors, is to prevent any considerable escape of gas through 70 the entrance and exit openings of the kiln, and to permit the cars to be progressively introduced into and withdrawn from the kiln. It will be seen from the above, that the cars are given a step by step motion through 75 the kiln. As the car is moved through the kiln, the rotary member 19 on the car in each section, strikes the arm 20 and frees the ashes, which fall upon the carrier 21 to be discharged external to the kiln. 80

The heating of the kiln is primarily due to the combustion of the gas derived from the gas and air burners 27, which impinges upon the body of refractory material 28 in the pockets 29, thereby effecting complete 85 combustion of the gas. The products of combustion then follow the direction indicated by the arrows, upward and downward through the body of fuel 41 in the car 11, thence through the openings 24 through flue 90 32 to flue 33 to blower 34, to be discharged into a gas receiver, not shown.

As the heat due to the products of combustion is not sufficient to completely disassociate the fuel in the car 11, the heat is 95 augmented by electric heat due to the passage of electric current from the dynamo 14 between the electrodes 23, the material 41 in the car serving as a resistance medium. The temperature of the fuel at this zone is 100 sufficient to disassociate CO₂ to form CO. The construction of this feature of the car is substantially the same as that disclosed in my prior U. S. Letters Patent No. 1,225,396 dated May 8, 1917. The gas derived from 105 the decomposing material, associated with the products of combustion, is carried out of the kiln through the flue 33. The temperature of the interior of the kiln can be regulated as desired, by controlling the independent gas and air burners 27 (see Fig. 4) and independent rheostats 15 (see Fig. 2). It will further be understood that by regulating the gas and air at the burners, the flame and the products of combustion 110 may exert either an oxidizing or a reducing effect, as desired, or the gas supply may be cut off at the burners and air introduced, where it is desired to aid combustion of the fuel in the cars, for any reason. 115

It will be observed that the heating effects, due to the combustion of the gas and air at the burners, are applied through radiation from the walls of the kiln and the sides of the car, as also by the convected heat carried by the vapor body passing through the fuel in the car on the way to the blower, and that the rapidity of motion of the vapor body can be regulated by the movement 125 of the blower 34. By controlling the differ- 130

ent heating means and the blower, perfect regulation can be obtained; also a large evolution of combustible gas effected.

Having thus described my invention, I 5 claim:

1. In a gas producer, the combination of a tunnel kiln, means for holding the material to be decomposed and progressively moving it through the kiln, means for heating the interior of the kiln, means whereby the heated gases set free in the kiln will pass through the material to be decomposed, and be discharged out of the kiln.

2. In a gas producer, the combination of a tunnel kiln, means for holding the material to be decomposed and progressively moving it through the kiln, means for heating the interior of the kiln, means whereby the heated gases set free in the kiln will 10 pass in a downward direction through the material to be decomposed, and be discharged out of the kiln.

3. In a gas producer, the combination of a tunnel kiln, means for holding the material to be decomposed and progressively moving it through the kiln, means for heating the interior of the kiln, means for heating a portion of the material to be decomposed to a temperature higher than the balance of the material, means whereby the heated gases set free in the kiln will pass through the material to be decomposed, and be discharged out of the kiln.

4. In a gas producer, the combination of a tunnel kiln, means for holding the material to be decomposed and progressively moving it through the kiln, means for heating the interior of the kiln, means for heating the material to be decomposed by the 35 passage of an electric current across the material using the material as a resistance medium, and means whereby the heated gases set free in the kiln will pass in a downward direction through the material 40 to be decomposed, and be discharged out of the kiln.

5. In a gas producer, the combination of a tunnel kiln, means for holding the material to be decomposed and progressively 50 moving it through the kiln, separately controlled gas and air burners located on opposite sides of the kiln, means forming part of the means for holding the material to be decomposed, for supplementing the heat set 55 free from the gas and air burners, and means for exhausting from the kiln the gaseous body produced.

6. In a gas producer, the combination of a tunnel kiln, a series of moving cars for 60 holding the material to be decomposed and progressively moving it through the kiln, means for heating the interior of the kiln, means whereby the heated gases set free in the kiln will pass through the material to 65 be decomposed, means for transmitting an

electrical heating current through a portion of the material to be decomposed, and means whereby the gases produced may be discharged from the kiln.

7. In a gas producer, the combination of a tunnel kiln, a series of cars adapted to be moved through the kiln and to carry the material to be decomposed, means for heating the interior of the kiln, means consisting of oppositely disposed electrodes carried by the cars and adapted to be energized from a source exterior to the kiln, for creating a zone of temperature in the material carried by the cars, in excess of that due to the heated gases set free in the interior of the kiln, means whereby the heated gases set free in the interior of the kiln will pass through the material to be decomposed, and means for exhausting from the kiln the gaseous body produced.

8. In a gas producer, the combination of a tunnel kiln, a series of cars adapted to be moved through the kiln, these cars having their side walls perforated at or near the bottom, separately controlled gas and air 90 burners on each side of the kiln, an exhaust blower located exterior to the kiln, flues within the kiln connected to the blower at one end and in communication with the openings in the sides of the cars at the other 95 end, and means interposed between the moving cars and the interior walls of the kiln whereby the products of combustion set free at the gas burners as well as the gas set free by the material on the cars, will pass 100 through the material, out of the openings in the walls of the cars, through the flues, and drawn from the kiln by the blower.

9. In a gas producer, the combination of a tunnel kiln, oppositely disposed rails arranged in the bottom of the kiln, one of said rails divided into sections and such rail and rail sections respectively connected to the opposite poles of a dynamo machine arranged external to the kiln, a series of movable vehicles in said kiln adapted to move over said rails, electrodes carried by said moving vehicles, rheostats interposed between the sections of one rail and one terminal of the dynamo, means separate from the electrodes for heating the interior of the kiln and the body of material to be decomposed, together with means for exhausting from the kiln the gaseous body produced.

10. In a gas producer, the combination of a tunnel kiln, a series of cars for holding the material to be decomposed and progressively moving it through the kiln, a series of revoluble grate bars carried by each car, means in the path of movement of said cars adapted to coact with said grate bars to cause their revolution and discharge ash, together with means for receiving the discharged ash and conveying it from the kiln.

11. In a gas producer, the combination of a tunnel kiln, means for holding the material to be decomposed and progressively moving it through the kiln, means for heating the interior of the kiln and the material to be decomposed, and means whereby the products of combustion and the heated

vapor set free within the kiln will be caused to move in a downward direction through the material to be decomposed and to be discharged from the kiln. 10

In testimony whereof I affix my signature.

GEORGE HILLARD BENJAMIN.
